UNITED STATES PATENT OFFICE.

DOUGLAS HAIGHT, OF COSHOCOTON, OHIO.

DESIGN FOR A WEATHER-VANE.

SPECIFICATION forming part of Design No. 33,547, dated November 13, 1900.

Application filed October 17, 1900. Serial No. 33,408. Term of patent 7 years.

To all whom it may concern:

Be it known that I, DOUGLAS HAIGHT, a citizen of the United States, residing at Coshocton, in the county of Coshocton and State of Ohio, have invented and produced a new and original Design for a Weather-Vane; and I do hereby declare the following to be a full, clear, and exact description of the invention, such as will enable others skilled in the art to which it appertains to make and use the same.

This invention relates to a design of novel form for a weather-vane. The characteristic feature of the design is the figure of a man standing upon an arrow and having wings projecting in opposite directions from the shoulders.

The drawing illustrates the design in elevation. The figure 1 is that of a man standing upon an arrow 2, from which a rod 4 is pendent. Wings 3 extend in opposite direc-

tions from the shoulders of the figure and are narrow at their inner ends and wide at their outer ends and are approximately of pear form.

The vane is designed to be used for advertising purposes and the matter to be displayed is inscribed upon the trunk portion of the figure, so as to be seen to the best advantage by the observer.

Having thus described the invention, what is claimed as new is—

The design for a weather-vane substantially as herein shown and described.

In testimony whereof I affix my signature in presence of two witnesses.

DOUGLAS HAIGHT. [L. S.]

Witnesses:

D. J. J. LOWER,

Jos. L. McDowell.
